Specification for Design.

Patented May 31, 1921.

Application filed September 3, 1920. Serial No. 408,034. Term of patent 14 years.

To all whom it may concern:

Be it known that I, JOHN TWEEDIE, a citizen of the United States, and a resident of the city of St. Louis and State of Missouri, have invented a new, original, and ornamental Design for Infant's Footwear, of which the following is a specification.

In the accompanying drawing, which forms part of this specification,

Figure 1 is a plan view of an infant's shoe embodying the design; and

Fig. 2 is a side elevation of the same.

I claim:

The ornamental design for infant's footwear, as shown.

JOHN TWEEDIE.
